UNITED STATES PATENT OFFICE.

MAY ROBSON, OF NEW YORK, N. Y., ASSIGNOR TO AUGUSTUS H. BROWN,
OF SAME PLACE.

ARTIFICIAL LEG FOR THEATRICAL PURPOSES.

SPECIFICATION forming part of Letters Patent No. 497,215, dated May 9, 1893.

Application filed March 23, 1893. Serial No. 467,248. (No model.)

To all whom it may concern:

Be it known that I, MAY ROBSON, of New York, in the county and State of New York, have invented a new and useful Artificial 5 Leg for Theatrical Purposes; and I do hereby declare that the following is a full and exact description thereof, reference being had to the accompanying drawings, and to the letters of reference marked thereon, making 10 a part of this specification.

The object of this invention is to produce a device by means of which burlesques of the popular skirt dancing can be produced with novel and startling effects.

15 To this end the invention consists in the provision of an artificial leg which is loosely attached to the person of the dancer and can be manipulated at the will of the dancer to produce as desired the semblance of extravagant and exaggerated poses, while ordinarily it hangs freely without inconveniencing the wearer and is concealed by the dress of the wearer.

20 In the drawings: Figure 1 is a view of the device ready for attachment to the body of the wearer. Fig. 2 is an outline view to illustrate the application of the device and the proper arrangement of the clothing.

The device comprises a representation A 25 of the lower portion of a human leg, which may be made of any suitable material but preferably is a hollow form of wood, cork or papier maché for the sake of lightness.

To the leg A are secured the means for 30 loosely supporting it from the person of the wearer. The simplest and most effective means for this purpose consist of a rod B fixed to the leg and a band or belt C which may be tied or otherwise fastened about the thigh or 35 the body of the wearer. The rod is connected to the belt or band by a simple loop c or such other means as will permit the leg to be moved freely in any direction. The rod affords a convenient means of attachment for 40 the leg as it occupies very little space within the clothing and at the same time may be grasped by the hand of the dancer to throw 45 the false leg into any desired position.

It will be found desirable to extend strong 50 elastic bands D, D, from different points on the waist-belt C to the rod B, or to the top of the false leg A, or to the top of the stocking E with which the false leg may be clad. If

these elastic bands are sufficiently strong they will of themselves raise the leg to an elevated 55 position as soon as it has been started by the hand of the dancer from its normal position.

In the use of the device it is preferred that the dancer should be clothed with the usual dancing skirts surrounding both of the lower 60 limbs and that the false leg should be clothed with independent skirts. The limbs of the dancer and the false leg with their skirts are then surrounded by an outer skirt. The result of this arrangement is that the false leg does 65 not interfere in the least with the free movements of the limbs of the dancer while the fact that the dancer is actually standing upon both feet when manipulating the artificial leg is concealed, and furthermore, that the 70 movements of the false leg become apparently more natural.

Many arrangements of cords, elastic bands, &c., might be employed for supporting and effecting the movements of the false leg, but 75 the arrangement described has been found to be sufficient for all practical purposes.

I claim as my invention—

1. As a theatrical appliance for use in burlesque dancing, a false leg provided with cords 80 or other suitable devices for supporting it loosely on the person so that it can move in any direction, and means whereby it can be moved at the will of the wearer; substantially as specified.

2. As a theatrical appliance for use in burlesque dancing a false leg, a rod secured thereto, and a belt or band to be secured about the person of the dancer, the rod being connected loosely to said belt or band, substantially as 90 shown and described.

3. As a theatrical appliance for use in burlesque dancing a false leg, a rod secured thereto, a belt or band to be secured about the person of the wearer, the rod being loosely connected to said belt or band, and elastic bands attached to the belt and connected to the false leg, substantially as shown and described.

In testimony whereof I have signed my name to this specification in the presence of 100 two subscribing witnesses.

MAY ROBSON.
